AIR LOCKED WINDOW

Joseph B. Liberty, Royal Oak, Mich.

Application February 29, 1944, Serial No. 524,470

5 Claims. (Cl. 160—91)

This invention relates to windows and it is one object of the invention to provide sash structure adapted to fit within a window frame and provide a window which is insulated by an air chamber against heat or cold and also serve to deaden noises which pass through a window of usual construction.

Another object of the invention is to provide a window structure wherein inner and outer sashes are carried by a frame, the outer sash being hinged at one side so that it may be swung outwardly to an opened position from within a room and the inner sash being so mounted that it may be very easily bodily removed from the frame.

Another object of the invention is to provide the window with inner and outer sashes having main sections and lower auxiliary sections mounted beneath the main sections, the lower auxiliary sections being movable out of a closed position independent of the main sections.

Another object of the invention is to so mount the sashes that they may be removed from the frame carrying the same and glass panes washed, the cleaned sashes being replaced without danger of injury due to leaning from a window or sitting upon a window-sill.

Another object of the invention is to so form the frame that the sashes will be held spaced from each other and have their outer surfaces flush with surrounding surfaces of the frame.

Another object of the invention is to provide a window structure of this character which is simple in construction, easy to install and operate, and can be manufactured and sold at small cost.

The invention is illustrated in the accompanying drawings wherein:

Figure 1 is a view looking at the outside of the improved window structure.

Figure 2 is a view looking at the inside thereof.

Figure 3 is a vertical sectional view taken along line 3—3 of Figure 1.

Figure 4 is a view showing the outside sash removed, the screen being still in place.

Figure 5 is a fragmentary sectional view taken along the line 5—5 of Figure 2.

Figure 6 is a fragmentary view showing a portion of the frame in perspective.

The frame 1 of this improved sash structure may be of any dimensions desired but is preferably of dimensions corresponding to those of a conventional window frame used in houses and other buildings for admitting light and air. If so desired it may be of such size that it may be fitted into a conventional window frame after the

usual sashes have been removed therefrom. A spacing strip 2 extends inwardly from the top and sides of the frame 1 midway inner and outer sides thereof and defines inner and outer channels or seats 3 and 4 to receive inner and outer sashes 5 and 6 and hold the sashes spaced from each other to provide a dead air space.

These sashes have upper main sections 5^a and 6^a and lower auxiliary sections 5^b and 6^b and are of such dimensions that they fit snugly into the channels or seats 3 and 4. Lower portions of the spacing strips 2 are reduced in width from their outer side edges to form inwardly offset recesses 7 to receive a screen 8, the thickness of the screen being such that its outer surface is flush with the inner wall of the channel 4 and of such height that its upper end portion is overlapped by adjoining ends of the two sections 6^a and 6^b of the outer sash. It should also be noted that the upper and lower sections of the sashes are of such thickness that their outer surfaces are flush with surrounding surfaces of the frame 1.

The upper section of the outer sash is hingedly mounted by hinges 9 at one side, for swinging movement from the closed position shown to an opened position in which it extends outwardly from the frame 1 and the lower section of the outer sash has its upper end connected with the lower end of the upper section by hinges 10 in order that it may be swung outwardly and upwardly to an opened position. Suitable fasteners, such as the latches 11 and 12, may be provided for holding the two sections of the outer sash closed but permitting them to be opened when pushed outwardly by a person in a room with which the window communicates.

The inner sash has its two sections free from each other and provided at their sides with rings 13 and 14 in order that a person may engage his fingers through the rings and individually withdraw the panels of sections from the frame. The upper section 5^a carries fastener members 15 adjacent its side edges which are spaced from each other longitudinally of the sash section, and from an inspection of Figure 3 it will be seen that when this upper section is thrust into the seat or channel 3 of the frame 1 the fastener members will engage between the jaws 16 of the companion fastener members 17 which are mounted against the spacing strips 2 and releasably hold the upper sash section in place. The lower sash section 5^b is also provided with latches at its opposite side edges which may be spring latches 18 formed as shown in Figure 5. Each of these latches has a casing 19 which is embedded in the

frame of the lower section and houses a spring 20 by means of which a plunger 21 is urged outwardly for engaging in a companion socket 22 carried by the frame 1. Since the two sections of the inner sash are free from each other either may be removed without disturbing the other. The panes of glass may then be cleaned and the sash sections replaced by a person within the room. By lifting the outer sash from its hinge it may also be moved into a room for cleaning of its glass panes and then replaced.

In order that the lower section 6^b of the outer sash may be opened without disturbing the screen the screen is formed midway the width of its lower end with a passage 23 for passage of an actuating rod or handle 24 through the screen. This rod has its forward end portion 24^a pivotally mounted and terminating in a pin 25 which fits into a socket 26 formed in the lower end of the lower section 6^b of the outer sash. When the lower section of the outer sash is closed the handle or rod 24 may be swung to a folded position in which it is disposed along the inner surface of the lower end of the screen where it will be out of the way and aid in holding the lower section of the outer sash closed.

Having thus described the invention, what is claimed is:

1. In a window structure, a frame formed along its sides and across its top with inturned recesses constituting inner and outer seats, lower portions of the outer seats having inwardly offset portions constituting auxiliary seats, inner and outer main and auxiliary sashes fitted into said frame and engaged in the inner and outer seats, the auxiliary sashes being under the main sashes, the outer auxiliary sash being hinged to the outer main sash, a screen in said frame engaged in the auxiliary seat, the outer auxiliary sash and the lower portion of the outer main sash bearing against the outer face of said screen, and fasteners for releasably holding the sashes in place.

2. In a window structure, a frame formed along its sides and across its top with inturned recesses constituting inner and outer seats, lower portions of the outer seats having inwardly offset portions constituting auxiliary seats, inner and outer main and auxiliary sashes fitted into said frame and engaged in the inner and outer seats with the auxiliary sashes under the main sashes, the outer main sash being hinged at one side to the frame for swinging movement to closed and opened positions, the outer auxiliary sash being hinged along its top to the lower end of the outer main sash for swinging movement to opened and closed positions and a screen in said frame engaged in the auxiliary seat and held therein by contact of the outer auxiliary sash with its outer face.

3. In a window structure, a frame formed along its sides and across its top with inturned recesses constituting inner and outer seats, lower portions of the outer seats having inwardly offset portions constituting auxiliary seats, inner and outer main and auxiliary sashes fitted into said frame and engaged in the inner and outer seats with the auxiliary sashes under the main sashes, the outer main sash being hinged at one side to the frame for swinging movement to closed and opened positions, the outer auxiliary sash being hinged along its top to the lower end of the outer main sash for swinging movement to opened and closed positions and a screen in said frame engaged in the auxiliary seat and removably held therein by the outer sash.

4. In a window structure, a frame formed along its sides and across its top with inturned recesses constituting inner and outer seats, lower portions of the outer seats having inwardly offset portions constituting auxiliary seats, inner and outer main and auxiliary sashes fitted into said frame and engaged in the inner and outer seats with the auxiliary sashes under the main sashes, the outer main sash being hinged at one side to the frame for swinging movement to closed and opened positions, the outer auxiliary sash being hinged along its top to the lower end of the outer main sash for swinging movement to opened and closed positions and a screen in said frame engaged in the auxiliary seat and held therein by the outer auxiliary sash, said screen having a passage intermediate the width of the lower end, and a rod for swinging the outer auxiliary sash outwardly and upwardly to an opened position passing through said passage and having its outer end engaged with the lower end of the outer auxiliary sash.

5. In a window structure, a frame formed along its sides and across its top with inturned recesses constituting inner and outer seats, lower portions of the outer seats having inwardly offset portions constituting auxiliary seats, inner and outer main and auxiliary sashes fitted into said frame and engaged in the inner and outer seats with the auxiliary sashes under the main sashes, the outer main sash being hinged at one side to the frame for swinging movement to closed and opened positions, the outer auxiliary sash being hinged along its top to the lower end of the outer main sash for swinging movement to opened and closed positions and a screen in said frame engaged in the auxiliary seat and held therein by the outer auxiliary sash, said screen having a passage intermediate the width of its lower end, and a rod for swinging the outer auxiliary sash outwardly and upwardly to an opened position passing through said passage and having its outer end engaged with the lower end of the outer auxiliary sash, said rod having a joint inwardly of the screen whereby the rod may be folded against the screen and extend transversely of the screen between the screen and the inner auxiliary sash.

JOSEPH B. LIBERTY.
